UNITED STATES PATENT OFFICE.

HARRY D. NEWMAN, OF MANASQUAN, NEW JERSEY.

CUFF-PROTECTOR.

1,239,944.

Specification of Letters Patent. Patented Sept. 11, 1917.

Application filed August 2, 1916. Serial No. 112,784.

To all whom it may concern:

Be it known that I, HARRY D. NEWMAN a citizen of the United States, residing at Manasquan, in the county of Monmouth, 5 State of New Jersey, have invented certain new and useful Improvements in Cuff-Protectors; and I do hereby declare the following to be a full, clear, and exact description of the invention, such as will enable others 10 skilled in the art to which it appertains to make and use the same.

This invention relates to cuff protectors designed to be applied to and cover a shirt cuff whereby to effectively prevent soiling 15 of the same. An object of the present invention resides in the provision of a cuff protector of simple and novel construction which may be conveniently attached to or detached from a shirt cuff.

20 A further object of the invention is to provide an article of this character which shall embody a pocket arranged to removably receive the outer edges of a shirt cuff and which shall further consist of novel 25 means for holding the protector snugly applied to the cuff.

Still another object of the invention is to provide a cuff protector which may if desired be also employed as a supplemental 30 cuff should the attached cuff of the shirt be soiled, frayed or otherwise unpresentable.

With the above and other objects of similar nature in view, the invention consists in the construction, combination and arrangement of parts set forth in and falling within 35 the scope of the appended claim.

In the drawing:

Figure 1 is a side elevation of the protector applied to a shirt cuff,

40 Fig. 2 is a sectional view taken on the line 2—2 of Fig. 1,

Fig. 3 is a transverse section on the line 3—3 of Fig 1, and,

45 Fig. 4 is a perspective view of the protector detached.

Referring now more particularly to the accompanying drawing, my improved cuff protector is designated generally at A and may be manufactured from material of any 50 desired nature such as linen, silk, madras, or other fabric. The protector may furthermore be manufactured of the same material as the shirt to which it is applied and will therefore serve not only as a protector but 55 as a supplemental cuff should the cuff of the

shirt itself become soiled, frayed or otherwise unserviceable.

The protector may consist of one or more plies of material patterned to fit the cuff of a shirt, and if more than one ply is employed they are suitably stitched together as indicated at 5 along their marginal edges.

Specifically the protector as a finished product comprises a substantially rectangular strip 6 longitudinally folded as indicated at 7 to provide an inner fold 9 and an outer fold 8, said inner fold being shorter than the outer fold and having its end edges stitched as at 10 or otherwise suitably joined to the corresponding edges of the outer fold whereby to provide an inwardly opening 65 pocket 11 adapted to removably receive and incase the free edge portion of a shirt cuff B as illustrated.

75 Provided in each end portion of the outer fold 8 adjacent to but outwardly of the longitudinal free edge portion of the inner fold is a button hole 12, which holes are adapted to register with each other and with the button holes 13 in the attached cuff B of the shirt whereby link buttons 14 or other conventional fasteners may be passed therethrough, the protector being in this manner positively secured to the cuff B 80 against accidental detachment.

85 There is further carried by one end of the outer fold 8 a tab 15 provided with a button hole 16, said tab being adapted to be folded to overlap the opposite end of the protector 90 when in applied position, while its button hole 16 is arranged to register with the button holes 12 in the outer flap whereby to receive therethrough the adjacent member of the link buttons 14.

95 The tab 15 will in this manner serve to hold the end portions of the folds snugly applied to the cuff B, rolling or curling of the edges of the flap to expose the surface of the cuff B being accordingly prevented. 100 The tab 15 furthermore provides a means by which the protector may be drawn tightly about the cuff and, when engaged with its button hole over the cuff link, will retain the protector snugly in place and insure it 105 against unsightly wrinkling.

110 It is understood that the device as a general rule is employed merely as a protector for the attached cuffs of a shirt and that when it has served its purpose it may be con-

veniently detached and carried, in the pocket for future use if desired.

What I claim is:

A cuff protector comprising connected inner and outer folds, the end edges of said folds being joined together to provide an inwardly opening cuff receiving pocket, said outer fold having cuff link receiving openings adjacent its ends registrable with the button holes of a cuff, and a tab carried by one end of the protector and by which the latter is

drawn snugly about a cuff, said tab being foldable to overlap the other end of the protector and having an opening therein to receive a cuff link and maintain the protector snugly in position. 15

In testimony whereof, I affix my signature in the presence of two witnesses.
